UNITED STATES PATENT OFFICE

OSCAR J. WOODEN, OF MILWAUKEE, WISCONSIN

DESIGN FOR A STORE FRONT

Application filed August 1, 1929. Serial No. 32,261. Term of patent 3½ years.

To all whom it may concern:

Be it known, that I, OSCAR J. WOODEN, a citizen of the United States, residing at Milwaukee, in the county of Milwaukee and State of Wisconsin, have invented a new, original, and ornamental Design for Store Front, of which the following is a description, reference being had to the accompanying drawing, forming part thereof.

In the drawing Figure 1 is a front elevation of the store, and Fig. 2 is a side elevational view.

I claim:
The ornamental design for a store front, as shown.

OSCAR J. WOODEN.
